RAZOR BLADE SHARPENING DEVICE

Hugh De Haven, New Canaan, Conn., assignor to
 De Haven Razor Corporation, a corporation of
 Delaware

Application June 20, 1930, Serial No. 462,519

17 Claims. (Cl. 51—158)

This invention relates to a razor blade sharpening device and the general object of the invention is such a device into which the razor and the blade may be placed and which may be operated 5 to sharpen the edge of the blade.

Another object of the invention is such a device which may be used as a box in which the razor may be kept when it is not being used for shaving and in which the blade may be sharpened 10 before the razor is taken out of the box.

A further object of the invention is such a device which may be used as a container for the razor and which cooperates with the razor to sharpen the blade when the said container is 15 shaken.

Other objects and features of the invention will more fully appear from the following claims taken in conjunction with the description and accompanying drawings which, however, must be 20 considered as merely illustrating and in no way limiting the invention to the embodiment shown and described.

The drawing illustrates in plan and section views selected forms of construction adapted for 25 the sharpening device and embody the broad principles of the invention.

In the drawing:

Fig. 1 is a plan view of one form of the blade sharpening device with the container open so that 30 the razor may be seen;

Fig. 2 is a vertical longitudinal section through the device shown in Fig. 1, with the container closed;

Fig. 3 is a section through a slightly different 35 form of blade sharpening device, with the container closed;

Fig. 4 is a plan view of the body of the container shown in Fig. 3, with the razor in sharpening position;

Fig. 5 is a side elevation of the razor shown in 40 Fig. 2, with the head of the razor in section; and

Fig. 6 is a side elevation of the razor shown in Fig. 3, with the head of the razor in section.

Only such parts of the device are shown as are 45 necessary to illustrate the broad principles of the invention, it being understood that various forms of razor and various forms of containers, sharpening elements and other parts for holding the razor and the blade may be used.

The device which is shown consists primarily 50 of a container adapted to receive the razor and blade and in which they are mounted for reciprocation relative to the sharpening element. The reciprocation may be obtained in any suitable manner but in the particular forms of the device

which are illustrated herein the razor and blade are loosely mounted within the container so that by shaking the container or tilting it from end to end the reciprocation of the blade and razor is accomplished due to the weight of the razor. 5 Within the container are one or more sharpening elements with which the edge of the blade may contact so that as the razor and blade reciprocate relatively thereto, the edge of the blade moves back and forth relatively to and in contact 10 with the sharpening elements to sharpen the edge of the blade.

In the form of device and razor which are illustrated in Figs. 1, 2 and 5, the razor consists of a handle 1, a head 2 and a blade holder 3 within 15 which the blade 4 is held. The base plate 5 of the razor head is preferably formed with guard teeth 6 on the front side. The blade holder or cap 3 is mounted on a shaft 7 having a flat side 8 so that the blade holder 3 either will remain in the 20 position shown in Fig. 2 or will be pressed toward the base plate 5 to hold the blade against the guard teeth 6. This action is obtained by making the blade holder or cap 3 of spring material and forming the parts as shown in Figs. 2 and 5 so 25 that the blade holder is held in the position shown in Fig. 2 by the flat side 9 of the blade holder bearing against the flat side 8 of the plate, and the blade holder or cap 3 is pressed toward the base plate 5 when the parts are in the position 30 shown in Fig. 5, by the tendency of the upper part 10 of the cap to lie flatly against the flat side 8 of the shaft 7. The blade is held within the blade holder by a clip 11 which is part of the 35 blade holder and which grips the backing 12 of the blade.

The container for the razor has a body 13 and a cover 14 which fit together, as is shown in Fig. 2. Within the container is a sharpening element 14 which is so placed that when the razor and blade are inserted within the container the blade is in contact with the sharpening element. The sharpening element 14 is also so placed that when the razor and blade move or reciprocate within the container, the edge of the blade moves over the sharpening element to sharpen the blade. One position of the sharpening element is illustrated in Fig. 2, in which the sharpening element 14 is on a part 15 of the container in such a position that it contacts with the edge of the blade when the razor is placed within the container with the cap in its open position. The handle of the razor is supported at the end 16 of the container in a suitable slot or groove so that the razor and blade may reciprocate length- 50 55

wise of the container (that is from the left to the right, or from the right to the left of Fig. 2) which causes the edge of the blade to reciprocate in contact with the sharpening element 14. It 5 will thus be seen that in the form of device shown in Figs. 1 and 2, the razor is not held within the container in fixed position and may easily be reciprocated by shaking the container. The distance between the sides 18 of the container 10 is preferably somewhat greater than the width of the razor and the slot 17 is somewhat greater than the diameter of the handle so that the razor may have a side reciprocating motion in addition to the longitudinal reciprocating motion. 15 The lower end 19 of the handle should be smooth in order to permit the razor to move readily within the container and an end plate 20 is provided within the container to serve as a stop to prevent the end of the handle from wearing 20 through the end of the container. The length of the longitudinal reciprocating stroke is determined by the end 19 of the handle contacting with the plate 20 when the razor moves to the right of Fig. 2 and by the plate 5 or side arms 25 of the razor head contacting with a stop plate 21 when the razor moves to the left of Fig. 2.

The sharpening element 14 is preferably provided with a raised portion 22 having a form substantially similar to that shown in Fig. 1, 30 from which it will be seen that when the razor and the blade are within the container there is a three-point support to enable the blade to contact evenly with the sharpening element, that is the handle of the razor is supported with- 35 in the groove 17 and the blade is supported on the two wings of the crescent or angular shaped raised portion of the sharpening element. This enables the blade to bear evenly against the raised portion 22 of the sharpening element, with 40 the result that all portions of the blade will be evenly sharpened as the blade reciprocates in contact with the sharpening elements; for instance, even if the blade is slightly warped the edge of the blade will contact evenly with the 45 raised portion 22 of the sharpening element, the edges 23 of the sharpening element being somewhat rounded to enable the edge of the blade to evenly contact therewith. The length of stroke which the razor may have when reciprocated 50 should be so regulated by the proper placing of the plate 21 with regard to the plate 20 that all portions of the edge of the blade contact with the raised portion 22 of the sharpening element so that the edge of the blade is sharpened 55 throughout its full length.

The weight of the razor will hold the blade in contact with the sharpening element but in order to give a greater pressure of the blade edge against the sharpening element, a spring 24 may 60 be fastened within the container to force the razor toward the sharpening element. The spring 24 is preferably a leaf-spring fastened to the cover of the container by the fasteners 25 so that the free end of the spring presses the 65 razor toward the sharpening plate with a yielding pressure which varies as the razor reciprocates, that is as the razor moves toward the left of Fig. 2 the pressure of the spring forcing the blade against the sharpening element decreases. 70 A ball or other suitable friction decreasing element 26 is preferably interposed between the cap 3 of the razor and the spring 24. The ball 26 may conveniently be held in place on the cap 3 by means of suitable keepers 27 which may be 75 struck up from the cap.

The tail or thumb-piece 28 of the cap 3, by which the cap may be moved into either of the 5 positions shown in Fig. 2 or Fig. 5, is preferably so formed that when the cap is in the position shown in Fig. 2, the end of the finger piece rests against the upper part of the razor handle, a groove or slot 29 being formed in the base plate 5 of the head of the razor in order to enable the finger piece to contact with the handle. This holds the parts as a fairly rigid structure when 10 the razor is within the container with the parts in sharpening position.

To sharpen the razor shown in Figs. 1, 2 and 5 it is only necessary to reciprocate the razor by shaking the box. This reciprocates the edge 15 of the blade in contact with the sharpening element 14. To sharpen the other side of the blade the container is opened, the razor is removed and the blade is then taken out of the blade holder 3 and turned over so that said other side 20 of the blade is in position to contact with the sharpening element 14. The razor is then returned to the box, the cover is put on and the box is again shaken to sharpen said other side of 25 the blade.

The razor blade sharpening device shown in Figs. 3, 4 and 6 is designed so that a plurality of sharpening elements 30 and 31 may be used. The sharpening element 30 is mounted in one part of the device, for instance in the body 13 of the container, and the other sharpening element 31 is mounted in another part of the device which may conveniently be the cover 14 of the container. The edge of the blade is held in contact with the sharpening element 30 by the weight 35 of the razor when the body of the container is lowermost but it will readily be seen that if the container is turned over so that the cover 14 is lowermost, the edge of the blade will contact with the sharpening element 31. This provides a convenient way of sharpening both sides of the edge 40 of the blade without removing either the blade or the razor from the container and without removing the blade from the razor. The sharpening elements 30 and 31 are preferably spaced and 45 the edge of the blade may be brought into contact with either one of them, as is desired. If the sharpening elements 30 and 31 have the same sharpening characteristics, that is, if they are of the same material and equally smooth, etc., each 50 side of the blade may be sharpened to the same extent by holding the container so that first one side of the blade and then the other side contacts with the sharpening elements and reciprocating the blade relatively to the sharpening elements; but the different sharpening elements 30 and 31 may have different sharpening characteristics, that is the sharpening element 30 may be rather rough to grind the blade edge rather than 55 polish it, whereas the sharpening element 31 may have a different characteristic and may be rather smooth to polish the edge of the blade rather than grind it, but both sharpening elements are preferably of material of such a hardness that the edge of the blade may reciprocate in contact with 60 them without nicking either the blade edge or the sharpening elements. From the previous description it will be seen that when the sharpening elements 30 and 31 have the same characteristics it is necessary only to hold the container as shown 65 in Fig. 3 and then shake it in such a way as to cause the edge of the blade to reciprocate in contact with the sharpening element 30, and to sharpen the other side of the blade it is necessary 70 only to turn the container over to bring the other 75

side of the blade edge into contact with the sharpening element 31 and then to shake the container in such a way as to cause the blade to reciprocate in contact with the sharpening element 31. If the sharpening element 30 is rather rough so that it has more of a grinding action than a polishing action on the blade edge, the container may be shaken to cause the reciprocation of the edge of the blade in contact with the element 30 to grind the blade edge. The container is then opened and the razor is turned over so that the other side of the blade edge is in contact with the grinding surface 30, whereupon the container may be shaken to grind the other side of the blade edge. Without removing the razor from the container, the container may be turned over so that the side of the blade which was first ground rests against the sharpening element 31 which has more of a polishing characteristic than a grinding characteristic. The container may then be shaken (with the cover 14 lowermost) to cause the reciprocation of the blade edge relative to and in contact with the polishing element 30. The container may then be opened and the razor again turned over to bring the other side of the blade edge in contact with the polishing element 31 and the container may again be shaken to polish the second side of the blade. It will thus be seen that the blade edge may be ground and polished on both sides in a relatively simple manner without removing the blade from the razor.

In the form of sharpening device shown in Figs. 3 and 4 the razor and blade also have a three-point suspension, that is the handle of the razor is supported at 32 or 33, depending upon which side of the container is lowermost, and the edge of the blade is supported on the crescent or angular shaped raised portion 22 of one or the other of the sharpening elements 30 and 31. This is in order to enable the edge of the blade to adjust itself for even contact with the sharpening elements. The length of stroke of reciprocation may be determined by any suitable stops. For this purpose the handle of the razor may be provided with a slot 34, and a pin 35 may project from the container in a position to enter the slot when the razor is in sharpening position. The engagement of the pin and either end of the slot determines the length of the sharpening stroke. The length of stroke of reciprocation should be such that the edge of the blade contacts with all of the raised portion 22 of the sharpening elements so that the blade is sharpened throughout its entire length, but the stroke should not be long enough to enable the edge of the blade to hit the end of the container, which would dull the blade edge.

The razor which may be used in this form of sharpening device is also of simplified construction. The blade holder may have the two blade gripping arms 36 and 37 so spaced that the blade may be slipped between them and from the sides of the blade holder the pins 38 extend for mounting the blade and blade holder in the head of the razor. The rear of the blade holder extends at 39 to be held either in the position shown in Fig. 3 or the position shown in Fig. 6 by detents 40 and 41, or any similar device which will accomplish the same result. If desired, the blade and blade holder may be a unitary structure and sold as a unit, as are some of the familiar razor blades now on the market.

The pins 38 may be on the sides 42 of the razor head, which may be of spring material so that the sides 42 may be spread apart to permit the pins

38 to enter sockets in the blade holder, or the pins 38 may be on the blade or the blade holder and may enter suitably spaced openings in the sides 42 of the razor head. The detent 41 preferably has a socket at its free end to fit exactly the rear 39 of the blade holder so as to hold the blade as shown in Fig. 3, but the socket on the free end of the detent 40 is preferably so curved that when the blade is in the position shown in Fig. 6, the rear portion 39 of the blade holder has not fully seated in the socket. This causes the detent 40 to continually press the blade against the guard teeth 6 to prevent any looseness of the blade when the razor is being used for shaving.

By the word "across" appearing in the claims, applicant intends to define the relative movement of the blade and sharpening element whereby there is a component of motion along a line from the blade edge toward the body of the blade as distinguished from the movement solely lengthwise of or parallel to the blade edge.

Although a particular and preferred form of the invention has been described, it is recognized that many various modifications may be made and it is therefore desired that the invention be construed as broadly as the claims, taken in conjunction with the prior art, may allow.

I claim:

1. In a device of the class described, a holder for a razor blade, a container capable of receiving the blade and the holder and in which they are mounted for reciprocation when the container is shaken, a sharpening element within the container the sharpening portions of the surface of which are in a plane and which surface is arranged to contact at non-continuous points with the blade edge and upon which the blade may reciprocate with the side of the blade in contact with the sharpening element, there being relative sharpening movement of the blade and element 40 across the blade edge, and means to prevent the blade edge from striking the container.

2. A razor blade sharpening device including a container, a sharpening element mounted therein, said container being capable of receiving a razor and in which the razor is mountable for relative reciprocation between the razor and the sharpening element, said sharpening element being placed for contact with the blade edge, and means to press the blade against the sharpening element as the relative reciprocation occurs with the blade and sharpening element in contact.

3. A razor blade sharpening device including a container for a razor, and a sharpening element for contact with each face of the blade, said razor being mountable in a container for relative reciprocation between the razor and said element, whereby the blade edge may be sharpened on both sides without removing the blade from the razor by reciprocating the blade and sharpening element relatively and in contact.

4. A razor blade sharpening device including a container, two spaced sharpening elements mounted therein, said container being capable of receiving a blade holder and in which the blade holder is mountable for relative reciprocation between the blade holder and the sharpening elements, said sharpening elements being placed for contact with the sides of the blade edge and at least one of the elements having ridges to move across the blade edge upon said reciprocation whereby both sides of the blade edge may be sharpened without removing the blade from the holder by reciprocating the blade and sharpening elements relatively and in contact.

5. A razor blade sharpening device including a container for a blade holder, and a plurality of sharpening elements mounted in said container and adapted to contact with the sides of a blade edge, said blade holder and sharpening elements being mounted for relative reciprocation across the edge of the blade, the surface of at least one of the elements having non-continuous points for contact with the blade edge whereby both sides of the blade edge may be sharpened without removing the blade from the holder by reciprocating the blade relatively to and in contact with the sharpening elements and means to limit the stroke of reciprocation.
15. 6. A razor blade sharpening device including a container for a blade holding element, a sharpening element mounted in the container for contact with one side of the blade edge and having a narrow contacting portion extending at an angle to the blade edge, and another sharpening element mounted in the container and spaced from the first sharpening element for contact with the other side of the blade edge, said blade holding element and sharpening elements being mounted for relative reciprocation and the blade and elements being relatively movable to allow the blade to contact with both sharpening elements, whereby both sides of the blade edge may be sharpened without removing the blade from the holder by reciprocating the blade and sharpening elements relatively and in contact.
25. 7. A razor blade sharpening device including a container for a blade holding element, a sharpening element mounted in one part of the container and having a broken line contact with one side of the blade edge, and a sharpening element mounted in another part of the container for contact with the other side of the blade edge, said blade holding element and sharpening elements being mounted for relative reciprocation, whereby both sides of the blade edge may be sharpened without removing the blade from the blade holding element by reciprocating the blade and sharpening elements relatively and in contact.
35. 45. 8. A razor blade sharpening device including a container for a blade holding element, a blade-holding element, a sharpening element mounted in one part of the container for contact with one side of the blade edge and a sharpening element mounted in another part of the container for contact with the other side of the blade edge, said elements operating by their weight to bring the blade edge and sharpening elements in contact, and said blade holding element and sharpening elements being relatively reciprocable whereby both sides of the blade edge may be sharpened without removing the blade from the blade holding element by reciprocating the blade and sharpening elements relatively and in contact.
50. 60. 9. A razor blade sharpening device including a container for a blade holder, a sharpening element mounted in one part of the container for contact with one side of the blade edge and a sharpening element mounted in another part of the container for contact with the other side of the blade edge and spaced from the other sharpening element, the blade holder being movable by its own weight between the two sharpening elements, said blade holder and sharpening elements being relatively reciprocable whereby one side of the blade edge may be sharpened by reciprocating the blade relatively to and in contact with one of the sharpening elements by holding the container in one position and the other side of the blade edge may be sharpened by re-

ciprocating the blade relatively to and in contact with the other sharpening element by holding the container in another position.

10. A razor blade sharpening device including a container for a blade holding element, a blade-holding element, said container having a body and a cover adapted to fit together, a sharpening element mounted in the body for contact with one side of the blade edge and a sharpening element mounted in the cover for contact with the other side of the blade edge, at least one of said elements being loosely mounted and movable by gravity within the container to bring a side of the blade edge in contact with a sharpening element, and said blade holding element and sharpening element being relatively reciprocable whereby both sides of the blade edge may be sharpened without removing the blade from the blade holding element by reciprocating the blade and sharpening elements relatively and in contact.

15. 20. 25. 30. 35. 40. 45. 50. 55. 60. 65. 70. 75. 11. A razor blade sharpening device including a container for a blade holding element, a blade-holding element, said container having a body and a cover adapted to fit together, a sharpening element mounted in the body for contact with one side of the blade edge and a sharpening element mounted in the cover for contact with the other side of the blade edge, said elements operating by gravity to bring the blade edge and sharpening elements in contact, and said blade holding element and sharpening elements being relatively reciprocable whereby both sides of the blade edge may be sharpened without removing the blade from the blade holding element by reciprocating the blade and sharpening elements relatively and in contact.

12. A razor blade sharpening device including a container for a blade holding element, a blade-holding element, said container having a body and a cover adapted to fit together, sharpening elements mounted in the container body and the cover for contact with the blade edge, said elements operating by gravity to bring the blade edge and sharpening elements in contact and said blade holding element and sharpening elements being relatively reciprocable whereby the sides of the blade edge may be sharpened by holding the container with the body or cover lowermost and to bring a side of the blade edge in contact with a sharpening element and reciprocating the blade and sharpening element relatively and in contact.

13. A razor blade sharpening device including a container for a blade holding element, a blade-holding element, sharpening elements mounted in different parts of the container for gravity contact with the sides of a blade edge without removing the blade holding element from the container and for relative reciprocation between the blade and sharpening elements, whereby the blade edge may be sharpened by permitting the elements to move by gravity to effect contact between the blade edge and a sharpening element and reciprocating the blade relatively to the sharpening element.

14. A razor blade sharpening device including a container for a blade holding element, sharpening elements mounted in different parts of the container for contact with the sides of a blade edge, said elements being mounted to provide relative reciprocation between the blade and sharpening elements and movement across the blade edge when the container is shaken, where-

by the blade edge may be sharpened by shaking the container to effect relative reciprocation between the blade and sharpening elements and effecting contact between the blade edge and a 5 sharpening element.

15. A razor blade sharpening device including a container for a blade holding element, sharpening elements mounted in different parts of the container for contact with the sides of a blade 10 edge without removing the blade from the container, gravity actuated means for holding the blade edge in contact with a sharpening element, the mounting of the elements being such as to permit relative reciprocating movement between 15 the blade and sharpening element and movement across the blade edge.
16. A razor blade sharpening device including a container capable of receiving a razor, sharpening elements mounted in different parts of the 20 container for contact with the blade edge without

removing the razor from the container and for relative reciprocation between the blade and sharpening elements and movement across the blade edge, the mountings being such that the blade edge can be brought into contact with any 5 sharpening element.

17. A razor blade sharpening device including a container, a sharpening element mounted therein, said container being capable of receiving a razor and in which the razor is mountable 10 for movement, a razor support within the container for supporting the razor with the blade in contact with the sharpening element and for relative movement between the blade and sharpening element whereby the blade may be sharp- 15 ened by placing the razor on the supports within the container and moving the razor to effect sharpening action between the blade edge and sharpening element.

HUGH DE HAVEN. 20
